UNITED STATES PATENT OFFICE

THOMAS O'NEILL, OF BROOKLYN, NEW YORK, ASSIGNOR TO THE SINGER MANUFACTURING COMPANY, OF ELIZABETH, NEW JERSEY, A CORPORATION OF NEW JERSEY

RIBBON SHIRRING DEVICE FOR SEWING MACHINES

Application filed July 15, 1929. Serial No. 378,196.

This invention relates to improvements in shirring attachments for sewing machines and more particularly to attachments for shirring ribbons and similar fabric strips. The present invention has for its primary objects to provide for effecting a uniform quality of shirring regardless of slight variations in the thickness of the work; to provide for readily determining different degrees of shirring of the strip; to permit of stitching the shirred strip during the shirring operation to a sleazy material without puckering said material; and still further to provide for readily shirring strips of different widths in the production of shirring effects of different characters.

In the shirring of fabric strips such as ribbons, during the operation of stitching a ribbon to an unshirred body material, a prior practice has been to feed the strip to be shirred faster than the unshirred material by either retarding the passage of the latter, as by means of a tension plate, or by wholly or in part removing the unshirred material from the direct action of the work-advancing means. The resulting products were consequently lacking in uniformity by reason of the uncertainty as to the extent of advance of the unshirred material during the formation of successive stitches.

In a preferred embodiment of the present invention, the strip to be shirred is directed to the stitch-forming mechanism by a ribbon-guide spaced above the body material placed upon the usual cloth-plate of a two-needle sewing machine. From substantially the point of penetration of the work by the needles, the strip to be shirred is directed at a downward inclination toward the body material, whereby the length of the strip between successive stitches is necessarily greater than the stitch-length as represented by the advance for each stitch of a body material effected by the action of a four-motion feed-dog assisted, preferably, by lateral movements of the needles while in the work. That the shirring effect upon the fabric strip is uniform will be readily understood by considering the downwardly inclined path of the strip as a constant comprising the hypotenuse of a

right triangle of which a shorter side is the body material from the point of convergence of said strip therewith to the vertical line of one of the descending needles.

In the present embodiment of this improvement, the ribbon-guide is shaped to bow the strip or ribbon upwardly substantially centrally of its width and is detachably carried by the sewing machine presser-foot so as to be readily exchangeable with others of different contours and widths. The extent of shirring of the strip is adjustably determined by changing the spacing of the strip from the body material at the needle penetration point, but might obviously be obtained in other ways as, for instance, by changing the angle of inclination at the delivery end of the guide. The presser-foot is constructed to provide spaced tread portions opposed to the feed-dog rearward of the needles, whereby sleazy body materials are positively advanced past the stitch-forming mechanism.

In the accompanying drawings, Fig. 1 is a longitudinal section of the free end of a sewing machine bracket-arm and of a portion of the cloth-plate, with the present improved presser-foot and ribbon guide in front elevation. Fig. 2 is a top plan view of the presser-foot and a portion of the cloth-plate. Fig. 3 is a view in side elevation of the present improved presser-foot, the needle and the feed-dog, with a portion of the cloth-plate in section. Fig. 4 is a sectional view substantially on the line 4-4 of Fig. 2. Fig. 5 comprises perspective views of the individual parts of the presser-foot, including the ribbon-guide. Fig. 6 is a perspective view of the feed-dog. Fig. 7 is a view of the delivery end of the strip-guide.

Referring to the drawings, the present improved shirring device has been embodied in a commercially well known sewing machine having a work-support comprising a cloth-plate 1 provided with slide-plates 2 and 3 upon opposite sides of a throat-plate 4. Overhanging the cloth-plate is a tubular bracket-arm 5 terminating in a head 6, pivotally supporting a swinging frame 7. Journaled for endwise reciprocation in suitable bearings in the frame 7 is a needle-bar 8, carrying at its

lower end two needles, as 9, spaced in a direction crosswise of the line of seam formation. Operatively connected with the frame 7 to impart swinging movements thereto is a bent 5 crank-arm 10 upon the end of a rock-shaft 11 journaled in the bracket-arm 5.

As disclosed in detail in, for instance, the U. S. patent to J. C. Ringe, No. 1,685,436, Sept. 25, 1928, the rock-shaft 11 is actuated 10 in timed relation with respect to the needle-bar endwise reciprocation to impart lateral movements to the needles 9 while said needles are in the work. These work-feeding movements of the needles occur in unison with the work-advancing movements of a four-motion feed-dog 12 provided with spaced apertures, as 13, within which apertures the needles 9 are disposed during the work-feeding movements thereof. The feed-dog 12 operates in the usual manner through suitable slots, as 14, provided in the throat-plate 4 and any suitable mechanism may be employed for imparting properly timed movements to said feed-dog. 15

20 Journaled for vertical movements in the head 6 is the usual spring-depressed presser-bar carrying at its lower end the present ribbon-guiding and shirring presser-foot. This presser-foot has a vertically disposed shank 16 fitted into a slot in the lower end of the presser-bar and secured to said bar by a screw 17. Extending forwardly from said presser-foot shank 16 are horizontally disposed, spaced arms, as 18, supporting 25 at the underside thereof a tread-block 19. The tread-block 19 is secured upon the arms 18 for adjustment in the line of seam formation by screws, as 20, passing through elongated slots, as 21, in said arms, steady- 30 ing means being provided by guide-pins, as 22, rising from the tread-block and entering elongated slots, as 23, in the arms 18 in alinement with the slots 21. At its rearward end, the tread-block 19 is provided 35 with a downwardly beveled ribbon-guiding surface 24 intersected by spaced parallel 40 needle-slots, as 25.

45 Secured for vertical adjustment upon the presser-foot shank 16 is the shank 26 of an auxiliary presser-foot, the securing means being afforded by screws, as 27, passing through vertically elongated slots, as 28, in said shank 26. This auxiliary foot has spaced treads, as 29, which are disposed 50 rearward of the needles to bear upon the work in the lines of seam formation in opposition to the spaced, narrowed rows, as 55 30, of the feed-dog teeth. The upturned toes of the treads 29 are joined by an arched bridge-piece 31, so that the shirred portion 60 of the work between the two seam lines is free from the pressure of the auxiliary foot. 65

Overlying the tread-block 19, is a ribbon-edge guide 32 provided along the opposite sides thereof with shouldered ledges,

as 33, engaged by angular clamp-plates, as 34, secured upon the arms 18 by the screws 20 and washers, as 35. Each of the clamp-plates 34 terminates at its rearward end in a downwardly bent ribbon-directing lip 36 70 spaced from the beveled surface 24 and affording a stop-shoulder 37 engaged by the delivery end of the ribbon-guide 32. The beveled tread-block surface 24 and the lips 36 are substantially parallel and together define a strip passageway inclined downwardly toward the work-support in the line of seam formation. The ribbon-guide 32 is in the form of a flattened tube, it being preferred to progressively arch said ribbon-guide from its comparatively flat receiving end toward its delivery end whereby a puffed effect is obtained in the shirred ribbon. However, the particular contour of the ribbon-guide and also the width between 75 its side guiding-walls are selective, it being evident that the guide-tube 32 may be readily withdrawn from the presser-foot by slightly loosening the clamp-plate securing screws 20, and may be replaced by other 80 guide-tubes of the desired form. 85

90 In the operation of shirring a ribbon and attaching it to an unshirred body material by spaced lines of stitches, the body material *m* is positioned upon the machine work-support below the tread-block 19 and the auxiliary-foot treads 29. The ribbon *r* to be shirred is inserted in the tubular guide 32 and is thereby directed to the needles. At the delivery end of said guide 32 the opposite margins of the ribbon *r* are directed 95 downwardly along the inclined surface 24 of the tread-block by the bent lips 36 of the clamp-plates. The ribbon *r*, stitched to the body material *m* then passes under the presser-foot treads 29. 100

105 The work-penetrating movement of the needles is in a path disposed approximately a stitch length in advance of the delivery end of the inclined surface 24 of the tread-block. Since the needles move laterally while in the work, they emerge from the work during their upward movement at a point where the ribbon *r* may be secured to the body material *m* in contacting relationship by the tightening of the stitch. Owing to the downward 110 inclination of the ribbon *r* between successive needle penetrations therein, a greater length of ribbon is incorporated in each stitch than the length of the body material, thereby causing the ribbon to be shirred. By adjusting the tread-block 19 in the line of seam-formation, the effective length of the incline may be changed to thereby vary the shirring effect. Also, by vertically adjusting the auxiliary presser-foot upon the presser-foot shank 16 to lower the treads 29 below the tread-block 19, the latter may be slightly raised above the body material to change the height of the incline 24 from the work-sup- 115 120 125 130

port and thereby vary the stirring effect produced upon the ribbon.

By employing the compound feed comprising the four-motion feed-dog and the feeding needles, the work-advance of both plies is definite for each stitch, in correspondence with the selected length of feed obtainable by means of the usual stitch-length adjusting means.

10 Having thus set forth the nature of the invention, what I claim herein is:—

1. In a sewing machine, a work-support, a reciprocatory needle, work-feeding means, guiding means including a fabric-strip guide and a bevelled fabric-strip supporting surface inclined downwardly toward said work-support from substantially the point of penetration of said strip by the needle, and means permitting adjustment of said inclined surface in the direction of feed relatively to said guide.

2. In a sewing machine, a work-support, work-feeding means, a plurality of reciprocatory needles spaced crosswise of and having laterally vibrating movements in the line of feed, a presser-foot opposed to said work-feeding means rearward of the path of said needles, and a guide terminating in advance of said presser-foot for supporting a fabric strip in spaced relation to the work-support at the point of penetration of said strip by the needles, the rearward end of said guide having a strip-supporting surface inclined to said work-support between successive points of penetration of the work by said needles.

3. In a sewing machine, a horizontally disposed work-support, a vertically reciprocatory needle, work-feeding means, a presser-foot having a tread-block in advance of the needle, a guide sustained by the presser-foot above said tread-block to direct a fabric in spaced relation to the work-support at the needle penetration point, an auxiliary presser-foot bearing upon the stitched work on the seam line thereof, and means for relatively adjusting said tread-block and auxiliary foot vertically.

4. In a sewing machine, a work-support, a reciprocatory needle, work-feeding means, a main presser-foot, a guide sustained by said presser-foot to direct a fabric strip in spaced relation to the work-support at the needle penetration point, an auxiliary presser-foot bearing upon the stitched work on the seam line thereof, and means for adjustably securing the auxiliary presser-foot upon the main presser-foot to thereby adjustably determine the extent of spacing of said guide from the work-support.

5. In a sewing machine, a work-support, a feed-dog projected above said work-support to advance the work, a plurality of vertically reciprocatory needles spaced transversely of the direction of feed, a presser-foot having a tread-block in advance of the needles ter-

minating in a downwardly beveled portion provided with needle-slots, a fabric-strip edge guide detachably secured upon said tread-block to deliver a fabric strip to the needles in spaced relation to said work-support, and an auxiliary presser-foot rearward of the needles.

6. In a sewing machine, a work-support, a feed-dog projected above said work-support to advance the work, a plurality of vertically reciprocatory needles spaced transversely of the direction of feed having lateral work-feeding movements, a presser-foot having a tread-block in advance of the needles terminating in a downwardly beveled portion provided with needle-slots, a guide disposed upon said tread-block to deliver a fabric strip to the needles in spaced relation to said work-support, and an auxiliary presser-foot rearward of the needles.

7. A sewing machine presser-foot comprising a shank provided with a forwardly extending supporting arm, a tread-block secured upon said arm for adjustment lengthwise thereof having a downwardly inclined rear end provided with parallel needle-slots spaced lengthwise of said inclined end, and a guide disposed to direct the edges of a fabric strip over the inclined end of the presser-foot, said presser-foot having spaced tread portions disposed rearwardly of and substantially in alignment with said needle-slots.

8. A sewing machine presser-foot comprising a vertically directed shank provided with horizontally disposed supporting arms, a tread-block carried by said arms having spaced needle-slots in its rear end, a strip-guide, means for detachably securing said strip-guide in position to overlie the tread-block, an auxiliary presser-foot having spaced tread portions disposed rearwardly of and substantially in alignment with said needle-slots, and means for securing said auxiliary presser-foot upon the presser-foot shank for vertical adjustment.

9. A sewing machine presser-foot comprising a vertically directed shank having forwardly extending spaced supporting-arms, a tread-block sustained by said arms for adjustment lengthwise thereof and provided at its rearward end with spaced needle-slots, a strip-guide bowed upwardly substantially centrally of its length, and clamp-plates carried by said arms for detachably securing the strip-guide in position to overlie said tread-block.

10. A sewing machine presser-foot comprising a vertically directed shank provided with forwardly extending spaced supporting arms, a tread-block sustained by said arms terminating in a downwardly beveled rear end provided with spaced needle-slots, a strip-guide, means for detachably securing said strip-guide in position to overlie the tread-block, and means for directing the

margin of a strip passed through said guide downwardly over the beveled rear end of the tread-block.

11. In a sewing machine, a work-support, a reciprocating needle, work-feeding means, means for supporting a fabric to be shirred in spaced relation to said work-support at the needle-penetration point, means for directing said fabric downwardly toward the work-support from the needle penetration point, whereby the length of the fabric between successive needle penetrations is greater than the stitch-length, and means for adjustably determining the height above the work-support of the fabric at the needle-penetration point.

12. In a sewing machine, a work-support, a reciprocating needle, work-feeding means, means for guiding a fabric-strip in a direction inclined to the work-support in the line of seam formation between successive points of penetration of the fabric-strip by the needle, whereby the length of the fabric-strip between successive needle penetrations therein is greater than the stitched length, and means for relatively shifting the needle and strip-guiding means in the line of seam formation during a stitch-forming cycle to effect the securing of the fabric-strip to the body material in contacting relationship therewith along the seam line.

13. In a sewing machine, a work-support, a reciprocating needle, feeding means for advancing a body material in a direction substantially parallel with the work-support, strip-guiding means including spaced substantially parallel guide-walls providing a fabric-strip passageway inclined to the work-support in the line of seam formation between successive points of penetration of the fabric-strip by the needle, whereby the length of the fabric-strip between successive needle-penetrations thereof is greater than the stitch length, and a strip-guide for directing the longitudinal edges of a fabric-strip to said guiding means.

In testimony whereof, I have signed my name to this specification.
